E. ISCHINGER

GUARD FOR PUNCH PRESSES

Filed June 9, 1922

INVENTOR

Eric Ischinger

UNITED STATES PATENT OFFICE.

ERIC ISCHINGER, OF EAST ROCHESTER, NEW YORK, ASSIGNOR OF ONE-HALF TO
FRANK KEIPER, OF ROCHESTER, NEW YORK.

GUARD FOR PUNCH PRESSES.

Application filed June 9, 1922. Serial No. 567,149.

The object of this invention is to provide a new and improved guard for punch presses which is simple in construction, efficient in its operation and readily applicable to any size and type of punch press.

This and other objects of this invention will be fully illustrated in the drawing, described in the specification and pointed out in the claims at the end thereof.

10 In the accompanying drawing:

Figure 1 is a side elevation of a punch press with the guard attached thereto.

Figure 2 is a front elevation of the punch press with the guard attached thereto.

15 Figure 3 is a detail perspective view of the assembled guard.

Figure 4 is an enlarged detail perspective view of the connecting members and joints of the guard.

20 In the several figures of the drawing like reference numerals indicate like parts.

Guards for punch presses are used to protect the operator of the machine from injury while operating the press. Any injury 25 caused by the press is either due to the carelessness of the operator or the failure of the press to operate properly. In either case, however, it can be guarded against by providing a guard member which operates to

30 swing in front of the ram of the press and in so doing brushes the operator's hands or fingers away from under the ram of the press before the punch and die are brought together. While guards for performing this

35 function have heretofore been made and marketed the guard forming the subject matter of my present invention is made so that it is applicable to all sizes and types of presses and can be applied in a short time

40 with a minimum expense where other guards are more or less restricted to the sizes and forms of presses for which they are designed, and are costly in their application due to the longer time it takes to apply them.

45 As illustrated in the figures of the drawing the guard comprises the oscillating member made up of the sleeve 1 which oscillates on the pivot pin 2. The pivot pin 2 is threaded into the frame of the press for

50 which purpose a suitable threaded hole may be provided or it may be threaded into the threaded hole of one of the gib screws 3 and take the place of the particular gib screw which it replaces. In either case the sleeve

55 1 is positioned on one side of the ram of the

press and in the particular case illustrated in the figures of the drawing at the left hand side thereof.

On the sleeve 1 and tangentially thereto are provided a pair of sockets or sleeves 5 and 4. Through these sockets or sleeves the eye bolt 6 and guard member 7 respectively may extend and be suitably fastened therein by means of set screws 9 and 8 respectively.

The eye bolt 6 forms an arm that projects from the oscillating member tangentially to the pivot pin 2 on which the oscillating member is mounted. The eye 10 of the eye bolt 6 engages into the bifurcation 11 on one side of the connecting block 12 and is suitably pivoted therein. The connecting block 12 is made up in the form of a short sleeve through which the eye bolt or link 13 may extend and be clamped into it by means of the set screw 14. The eye 15 of the eye bolt 13 is adapted to be pivoted to the ram of the press by means of the bolt 16 so that on the reciprocation of the ram of the press the oscillating member 1 is oscillated at each stroke of the press through the train of connections above described.

The guard member 7 carries on its lower end the wing or gate 7^A. This wing or gate is normally held in position on one side of the ram of the press at the beginning of each stroke of the press. As soon as the ram descends, however, the eye bolt connection of the ram with the oscillating member swings the guard member and wing across the front of the press and brushes the operator's hand aside, before the punch and die mounted on the press are brought together on the downward stroke of the ram of the press.

The connections between the eye bolts 6 and 13 with the connecting block 12 and oscillating member 1 are adjustable in that each of these members can be made shorter or longer by extending it a shorter or longer distance through the sleeves formed in each of these members and clamping them in place in these positions. This also holds true of the connection of the guard member 7 with the oscillating member 1 which allows the gate on the guard member to be raised and lowered according to the need of the particular press to which it is applied.

With these possible adjustments of all the members of the guard the guard can be applied to all sizes and types of presses and if

found necessary the eye bolts or links 6 and 13 as well as the guard member 7 can be bent to conform to or clear the parts of the frame of the press on the front of which 5 they operate.

I claim:

1. In a guard for a punch press, the combination of an oscillating member, a pivot pin mounted on the frame of the press on 10 which said oscillating member is mounted, a socket formed on said oscillating member, a link extending into said socket and adapted to be adjustably held in place herein, a connecting block pivoted to the outer end of 15 said link, a second link adapted to be adjustably clamped to said connecting block, and means for connecting said second link to the operating part of the press.
2. In a guard for a punch press, the combination of an oscillating member, adapted 20 to be mounted on the frame of the press, a pair of sockets formed on said oscillating member, a link adapted to be adjustably held in one of said sockets, a guard member 25 adjustably clamped into the other of said sockets, a second link adjustably connected to the outer end of said first named link and means to connect said second named link to the operating member of said press.
3. In a guard for punch presses, the combination of an oscillating member adapted 30 to be mounted on the front of the press, an arm carried by said oscillating member and adjustably fastened thereto, a link connect- 35 ed to said arm and connecting said arm with the front of the ram of the press, means for lengthening and shortening the link connection between the ram of the press and said arm, a guard arm carried by said oscillating member and adapted to be swung across the 40 front of the frame of the press on the oscillation of said oscillating member and adapted to swing in a plane parallel to the plane of movement of the ram of the press.
4. In a guard for punch presses, the com- 45

bination of a pivot pin mounted in the face of the press adjacent to the ram of the press, an oscillating member mounted on said pivot pin, a sleeve formed on said oscillating member, an arm adjustably mounted 50 in said sleeve, a link connected to the end of said arm, said link connecting the ram of the press with the end of said arm, means provided on said link to lengthen or shorten the connection between said ram and said 55 arm, a second sleeve formed on said oscillating member at an angle to said first sleeve formed thereon, a guard arm adjustably mounted in said second sleeve.

5. In a guard for punch presses, the combination of a pivot pin, an oscillating member mounted on said pivot pin, a pair of sleeves provided on said pivot member one behind the other and projecting from said oscillating member, one of said sleeves being adapted to adjustably hold an arm in place on said oscillating member and the other of said sleeves being adapted to hold a guard arm adjustably in place on said oscillating member.

6. In a guard for punch presses having a ram, the combination of a pivot pin mounted on the frame of the press, an oscillating member mounted on said pivot pin, a separate arm carried on said oscillating member, said arm being adjustable endwise at right angles to said pivot pin, a link pivotally connected to one end of said arm, a second pivot pin mounted on the ram of the press below said first pivot pin on the frame 70 of the press and at one side thereof, said link being pivoted at one end thereof to said arm and being also pivoted at the other end thereof to said second pivot pin on said ram, a guard arm carried by said oscillating 75 member, said link and said arm forming a permanent but adjustable connection between said ram and said oscillating member.

In testimony whereof I affix my signature.

ERIC ISCHINGER.
